Filed June 21, 1965, Ser. No. 465,328
5 Claims. (Cl. 239—579)

This invention relates to dispensing valves for controlling the discharge of materials from a container under pressure. More specifically, it pertains to specialized valves for dispensing material in massive quantities or at high velocity.

While standard material dispensing valves, having a longitudinally reciprocable operator, meet the requirements of most applications, it has been found that certain applications require dispensing characteristics that such standard valves cannot meet. For instance, the standard dispensing valve cannot produce the massive discharge that is required for applications such as fire extinguishers or the like, nor can it produce the high velocity discharge which would be required to effectively dispense syrups or the like, where it is desired that the material be simultaneously dispensed into and mixed with another substance.

It is, therefore, an important object of the present invention to provide a material dispensing valve, having a longitudinally reciprocable operator, capable of dispensing material from a container in a specialized manner, such, for example, as in massive quantities, on each operation of the valve, or at high velocity.

According to the invention, the foregoing object is achieved by forming the valve to include a housing, through which all the material to be dispensed must pass, and providing the housing with inlet and outlet ports communicating the interior thereof with the material container and atmosphere, respectively. In accordance with the invention, it is essential, whether the valve is intended to dispense the material in massive quantities or at high velocity, that the inlet and outlet ports be so related to the housing as to permit massive quantities of material to pass therethrough at any given instant on each operation of the valve. In other words, the cross-sectional area of the inlet and outlet ports must be sufficiently great relative to the cross-sectional area of the valve housing as to permit a maximum of material to pass through the housing to be dispensed therefrom. It is also important, in order to obtain a massive flow of dispensing material, that the outlet port be of at least as great cross-sectional area as the inlet port, thereby preventing the flow of material from being interrupted as by slowing it down or limiting it.

In order to obtain high velocity discharge from the valve, the valve described above, which produces a massive material discharge, is modified by substantially restricting the flow of material from the outlet port to the atmosphere, thus causing the material to build up behind the restriction and the pressure thus created to supplement the pressure in the container for dispensing the material at a high velocity.

Another object of the invention is to provide a valve for dispensing material in massive quantities from a container under pressure, which includes a longitudinally reciprocable valve stem guidably mounted in a housing through which all the material being dispensed must pass, the valve stem being formed to cooperate with the housing for providing an inlet port for openly communicating the interior of the housing with the container and an outlet port for communicating the interior of the housing to the atmosphere when the stem is moved to discharge position, the inlet and outlet ports each being of large cross-sectional area relative to the cross-sectional area of the housing for passing large quantities of material at

2

any given instant through the housing, whereby massive material discharge is achieved.

Another object of the invention is to provide a dispensing valve having a longitudinally reciprocable valve stem guided in openings in opposite ends of a valve housing through which all of the material being dispensed must pass, the opposite ends of the valve stem being formed with longitudinally extending ribs defining passages cooperatively forming an inlet port at one end of the housing and an outlet port at the opposite end thereof, the inlet and outlet port each having an overall cross-sectional area which is relatively large compared to the overall cross-sectional area of the housing, whereby large quantities of material may be passed through the housing at any given instant.

Still another object of the invention is to provide a dispensing valve, having a housing through which all the material being dispensed must pass and a longitudinally reciprocable valve stem guidable in openings in opposite ends of the housing, the valve stem and opposite ends of the housing cooperating to form inlet and outlet ports for passing material through the housing, wherein the inner end of the housing is formed with a plurality of openings for supplementing the inlet port so that the overall cross-sectional area of the inlet port is relatively large relative to the cross-sectional area of the housing and wherein the outlet port is of at least as great cross-sectional area as the overall cross-sectional area of the inlet port, whereby a massive quantity of material may pass through the housing at any given instant.

It is further an object of the invention to provide a dispensing valve for dispensing material under pressure from a container which includes a housing through which all the material being dispensed must pass, a longitudinally reciprocable valve stem cooperating with the housing for forming inlet and outlet ports for passing massive quantities of material through the housing at any given instant on operation of the valve, and means for restricting the flow of material from the outlet port, whereby the material flow builds up pressure behind the restriction for supplementing the pressure dispensing the material from the container so that the material is dispensed to the atmosphere at high velocity.

It is still further an object of the invention to provide a dispensing valve operable in an upright position and having a longitudinally reciprocable valve stem for operating the valve and passing all of the material being dispensed through a valve housing, which dispenses massive quantities of material on each operation of the valve and, with only a minor modification of the material outlet, dispenses the material at high velocity.

An advantage of the present invention resides in the fact that a standard material dispensing valve, of the type including a housing through which all the material being dispensed must pass and a longitudinally reciprocable valve stem for operating the valve, with only minor modification of the valve stem and/or housing, to provide inlet and outlet ports of relatively large cross-sectional area relative to the cross-sectional area of the valve housing, may be converted to a specialized valve construction for dispensing massive quantities of material and, with the further addition of a means for restricting the massive flow of material from the outlet port of the valve, for dispensing material at high velocity.

A further advantage of the present invention is that the specialized type of material discharge achieved, namely massive quantity or high velocity, is obtained through a construction that may be operated in an upright position, whereby it may be applied to a wide variety of applications and used in conjunction with a wide variety of directional nozzles, applicators or the like.

Other objects and advantages of the invention will be apparent from the specification and claims, when considered in connection with the attached sheet of drawings, illustrating one form of the invention, wherein like characters represent like parts and in which:

FIGURE 1 is a fragmentary elevational view, in section, illustrating a material dispensing package embodying a dispensing valve according to the invention, in non-discharge position, for dispensing massive quantities of material on each operation of the valve;

FIG. 2 is similar to FIG. 1, but shows the valve in discharge position;

FIG. 3 is also similar to FIG. 1, but shows the valve modified to provide a construction for dispensing material at high velocity;

FIG. 4 is a cross-sectional view taken in the direction of the arrows 4—4 in FIG. 1;

FIG. 5 is a cross-sectional view taken in the direction of the arrows 5—5 in FIG. 1; and

FIG. 6 is a cross-sectional view taken in the direction of the arrows 6—6 in FIG. 1.

Referring now to the drawings, the valve means of the instant invention, generally indicated by the numeral 10, is shown as part of a conventional material dispensing package 11, the package including, in addition to the valve means, a container 12 for holding the material (not shown) to be dispensed under pressure therein and mounting means 13 for mounting the valve means on the container, whereby discharge of the material therefrom is controlled. As illustrated in the drawings, while the valve means may be utilized with substantially any conventional dispensing package and in conjunction with material containers of any well known type, the valve means 10 is here shown as part of, what might be termed, an upright dispensing package and is sealably mounted in the open neck 14 of a bottle type container by the mounting means 13.

With reference now to FIGS. 1, 2 and 4 through 6, in particular, the valve means, which in this embodiment of the invention is intended to dispense a massive quantity of material on each operation of the valve, is seen to include a valve housing 15, of substantially tubular form, having its upper end secured in a mounting cup 16, forming part of the mounting means 13, and its lower end disposed within the interior of the container 12. The mounting means 13 mounts and supports the valve means 10 in the open end of the container through a mounting flange 17 formed integral with the mounting cup, the mounting flange being connected to the neck of the container by rolling, crimping or similarly securing it therover, as is well understood in the art. In order to seal the interior of the container from the atmosphere and close its open end, a resilient sealing ring 18 is provided, having a central bore therethrough, which is clamped between the mounting flange 17 of the mounting means 13 and the top edge of the container neck 14, the valve housing 15 extending through the bore in ring 18 and being sealably gripped thereby.

The valve housing 15, which is common to many types of dispensing valves and provides a chamber 19 through which all the material to be dispensed must pass, has a transverse wall 20 at the inner end thereof, formed with a bore 21 for communicating the interior of the housing or chamber 19 to the container, and a resilient means, in the form of a disk 22 having a bore 23 therethrough, clamped between the upper end of the housing and the mounting means, for forming an outer end wall. As will be readily understood, the valve housing may be formed with a depending skirt 24 for receiving the conventional dip tube 25 and may also be formed with an integral depending stud 26, having a bore therethrough forming a continuation of the bore 21, for frictionally supporting a small diameter dip tube (not shown), if desired. It is noted that in the illustrated form of valve means, the depending stud 26 is provided with a plurality of longitudinally

extending, radially spaced ribs 27 for pressing the dip tube 25 into engagement with the inner surface of skirt 24, the ribs being tapered at their leading end to facilitate insertion of the dip tube.

5 The valve housing thus far described movably carries a valve stem or valve operator 28, which has an inner end 29 guidably received in the opening 21 in inner end wall 20 of the housing and an outer end 30 guidably received in the bore 23 of outer end wall disk 22. The valve stem, which is longitudinally reciprocable and normally resiliently urged by a spring 31 to project its outer end 30 outwardly of the housing, is formed with an enlarged intermediate portion 32 providing a shoulder 33 for engaging the underside of resilient end wall disk 22, when the valve stem is in normal position, for sealing the interior of the valve housing from the atmosphere.

As is common in valve constructions of this type, the valve stem cooperates with the valve housing to provide inlet and outlet ports for the chamber 19 whereby, on movement of the valve stem against the spring 31, the material to be dispensed is enabled to pass through the valve housing from the container to the atmosphere. In prior dispensing valves the inlet port normally comprised an open, relatively small, passage between the inner end wall of the housing and the end 29 of the valve stem while the outlet port comprised a passage in the end 30 of the valve stem having an opening thereto disposed adjacent the enlarged intermediate portion and normally positioned outwardly of resilient end seal 22. When it was desired to dispense material from the container, the valve stem was moved inwardly against the spring 31 to break the seal between enlarged valve stem portion 32 and resilient disk 22 and move the opening of the outlet port into the chamber 19, thereby enabling the material to move, under the pressure in the container, through the valve housing and outwardly to the atmosphere.

While the prior valve constructions permitted continuous discharge of material from the container, it has been found that in order to obtain a massive discharge, that is, the passage of a large quantity of material through the housing at any given instant, the cross-sectional area of the inlet and outlet ports must be sufficiently great relative to the overall cross-sectional area 40 of the housing to permit a maximum amount of material to pass into and out of the housing at any given instant. According to the present invention, this is achieved, without substantially effecting the guiding relationship between the valve housing and the valve stem, by forming the inner end 29 and outer end 30 of the valve stem with longitudinally extending radially spaced ribs 34 and 35, respectively. The ribs 34 and 35 which bear against the valve housing in the openings through which their respective stem end portions project for maintaining the guiding relationship between the valve housing and valve stem, cooperatively provide passages or channels 36 and 37, respectively, the passages 36 cumulatively forming inlet port means for openly communicating the interior 45 of the housing to the container and the passages 37 cumulatively forming the outlet port means whereby the interior of the housing is communicated to the atmosphere when the valve stem is moved to discharge position.

While it is possible within the concept of the present invention that the valve stem construction above described will provide inlet and outlet port means of sufficient size to assure a massive flow of material through the valve housing at any given instant, in the preferred form of the invention illustrated the inner end wall 20 is formed with a plurality of radially spaced openings 38 disposed circumferentially around the central opening 21 which receives and guides the inner end of the valve stem. The additional communication provided, between the interior of the housing and the container, by

the openings 38 supplements the communication provided by the passages 36 and forms therewith an inlet port means having an overall cross-sectional area of sufficiently great size relative to the cross-sectional area of the housing for assuring the flow of a large quantity of material into the housing.

It should here be noted, that in order to obtain the desired massive discharge of material, the outlet port means should be of at least as great cross-sectional area as the inlet port means. In the illustrated form of the invention this is achieved by forming the outer end portion of the valve stem to have a greater diameter than the inner end portion, thus increasing the overall cross-sectional area of the passages 37 formed therein.

The dispensing valve 10, above described, may, as shown, be provided with a combined actuating button and directional dispensing nozzle 39 for directing the flow of material being discharged through the outlet port means. As will be seen, the button 39 is formed with a passage 40 of at least as great cross-sectional area as the outlet port means and is provided with a depending skirt 41 for confining the passages 37 to direct the flow of material through the outlet port means and thence to the passage 40. The skirt 41 preferably ends sufficiently short of the ends of the passages 37, or is spaced from the enlarged intermediate portion of the valve stem, a distance sufficient to assure an uninterrupted flow of material from the housing into the outlet port means when the valve stem is moved to discharge position.

The material dispensing valve 10, above described in connection with FIGS. 1, 2 and 4 through 6, which is adapted to provide a massive discharge of material from the container 12 on each operation of the valve, may be modified with respect to the shape, form or location of its parts, including the inlet and outlet port means, without departing from the concepts of the invention, so long as the desired relationship between the size of the inlet and outlet ports relative to the housing is maintained; the inlet and outlet ports must be large enough to assure a massive flow of material through the housing at any given instant.

Referring now to FIG. 3 of the drawing, the dispensing valve 10 is shown modified to produce a high velocity discharge of material. This valve is essentially identical to the massive discharge valve described above, but is provided with means, here shown as a plug 42 disposed in the passage 40 of the button 39 formed with an orifice 43 of very small cross-sectional area relative to the valve outlet port means, for restricting the flow of discharging material, whereby the pressure produced by the discharging material backing up behind the restriction supplements the pressure in the container to dispense the material at high velocity.

It is noted that, while the size of the orifice 43 relative to the overall size of the outlet port means may vary over a wide range so that control over the velocity of the discharge may be achieved, it is contemplated the cross-sectional area of the orifice shall not be greater than 95 percent of the cross-sectional area of the outlet port means nor less than 5 percent thereof. Further, it is noted that, while the restriction provided by the orifice 43 is here produced by utilizing an insert or plug 42 disposed in the actuator button 39, the restriction may take many other forms, such as by forming it as an integral part of the valve stem itself, a reduction in size in a portion of the outlet port means, or as an integral part of the actuator button or the like.

Thus, among others, the several objects and advantages

of the invention as aforenoted are achieved. Obviously numerous changes in the structure may be resorted to without departing from the spirit of the invention as defined by the claims.

I claim:

1. A dispensing valve for controlling the discharge of material in massive quantities from a container having the material under pressure therein comprising a substantially tubular housing having a transverse wall provided with a bore at the inner end thereof and a chamber at the outer end through which all material being dispensed passes; resilient means having a bore therethrough closing said housing and forming an outer end wall of said chamber; means for mounting said housing in an opening in the container for closing the same; a valve means slidably mounted in said housing for controlling the dispensing of the material from the housing, said housing having a plurality of longitudinal passages in the walls thereof extending from the chamber to the container to pass massive quantities of material therethrough, said valve means having an outer portion extending from said container and provided with a button on the outer end and having a dispensing nozzle, said button having enlarged passages communicating with a longitudinal passage means in said portion; and means normally urging said valve means into an outwardly projected non-dispensing position; said outer end portion of said valve means being formed with outlet port means normally disposed outwardly of said resilient means and sealed thereby from the chamber of said housing, the longitudinal passage means in said portion readily passing the material received from said longitudinal passages in the housing to dispense the material from the chamber upon said outlet port means being moved inwardly of said resilient means to a discharge position against said urging means, whereby massive quantities of material are dispensed from said container through said plurality of longitudinal passages in the housing to the chamber and through said outer portion to the enlarged passages in the dispensing nozzle.

2. The invention as defined in claim 1 wherein the bore in the transverse wall communicates with the container and the valve means has a portion thereof comprising a plurality of ribs for engaging the walls of the bore for guiding the portion and also providing additional passages for the material communicating with said chamber.

3. The invention as defined in claim 1 wherein the valve means includes a unitary stem member having ribbed upper and lower portions providing a plurality of longitudinal passages for movement of the material to and from the chamber.

4. The invention as defined in claim 1 wherein the projecting portion of the valve means has a ribbed cross-section and said button has a sleeve surrounding said projecting portion to form said longitudinal passage means in the said valve means.

5. The invention as defined in claim 1 wherein a member having a restricted orifice is provided in the discharge nozzle to provide increased pressure for the high velocity discharge of said material.
